[57] ABSTRACT

The invention relates to a temperature responsive switch assembly of the type having a pivotally mounted lever attached to a snap action spring with the lever being pivotally movable in response to opposing forces provided by a rated spring and a vapor containing working element. The moving contact of the switch is attached to the lever. Although the vapor pressure curve of the working element is not linear, the temperature differentials between the switch on and off temperatures are kept substantially constant for the whole range of nominal temperature settings for the system. This object is achieved by an arrangement in which the line of force of the rated spring forms an acute angle with the lever which angle is of a selected magnitude that compensates for the nonlinearity of the vapor pressure curve of the working element is provided.

TEMPERATURE RESPONSIVE SWITCH

The invention relates to a temperature responsive assembly of the snap action type. The assembly comprises a rigid lever, a snap action spring, a vapor containing working element and an adjustable rated-value spring which counteracts the working element.

In switches of the kind here considered, the snap action spring in particular a spring having the shape of the Greek letter omega, has a negative spring characteristic in the working direction. The snap over action therefore takes place when the difference between the forces applied by the working element and the rated-value spring exceed the force of the snap action spring in the rest position. These switches are therefore called "force-proportional" springs in contrast to "distance-proportional springs" in which at least one lever of the snap action system must be moved through a dead-cent position before the snap-over action takes place.

Since the vapour pressure curve is not linear, the temperature difference, i.e., the difference between the switch-on temperature and the switch-off temperature varies with each nominal temperature to which the system is set. It is however desirable to keep this difference approximately constant over the entire working range. It is therefore known practice in the case of temperature responsive actuating devices comprising a vapor containing working element and a rated value spring, so to design this spring that the steepness of the spring characteristic curve increases as the spring force rises, so that the spring characteristic curve resembles the vapour pressure curve. In the case of force proportional temperature responsive switches, compensation cannot be achieved in this way.

A force proportional temperature responsive switch is known in which use is made of a double-armed lever. The working element and the rated value spring are arranged side-by-side, one on each side of the point of rotation, and act on the lever over an angle of 90°.

In another force proportional switch, the working element and the rated-value spring are arranged coaxially with each other. They engage a common rod. The rod transmits the difference in force to the lever.

The object of the present invention is to provide a force proportional temperature responsive switch which is at least partially compensated.

According to the invention this object is achieved by an arrangement in which the line along which the rated value spring applies force forms with the lever an angle that deviates from 90° to an extent such that the effect of the bend in the vapour pressure curve on the difference in the switching temperatures is at least partially compensated.

Such compensation is achieved if the line along which force is applied by the rated value spring forms an angle of less than 90° with that portion of the lever presented to the point of rotation.

It has proved particularly advantageous if the angle between the line along which the force of the rated value spring is applied and the lever is 60 - 80°, and preferably 65 - 75°.

If the line along which the rated value spring applies force is inclined in the manner described, a very surprising result is that the steepness of the characteristic curve of the spring force acting on the lever decreases as said force increases. A curve of this kind, however, is precisely what is required in a force proportional switch in order to compensate at least partially the cur-

vature in the characteristic curve of the spring. Conversely, the aforementioned slope of the line along which the force of the working element is applied leads to the curve of the vapor pressure, that acts on the lever, becoming less pronounced.

A particularly space saving construction is obtained if the lever consists of two arms which form an obtuse angle with each other, and if the rated value spring engages that arm remote from the snap action spring and extends substantially parallel with the arm presented to the snap action spring. The switch can then be formed as a very compact unit by fitting the working element and the contact system side-by-side on that side of the arm presented to the snap action spring that is opposite the rated value spring.

The invention will now be described in greater detail by reference to the attached drawing, in which:

FIG. 1 is a diagrammatic illustration of a form of construction in accordance with the invention.

FIG. 2 is a graph of the vapour pressure curve and the forces occurring at the springs,

FIG. 3 is a longitudinal section through a temperature responsive switch in accordance with the invention, and

FIG. 4 is a cross section on the line A—A of FIG. 3.

The temperature responsive switch comprises a snap-action system which consists of a double-armed lever 1 and a spring 2 of the shape of the Greek letter omega. The lever is adapted to rotate about a pivot 3 solid with the casing. It forms a link 4 with the spring 2. This spring is secured on a backing element 5 which is solid with the casing and which may be adjustable. The lever consists of two arms 6 and 7. The force P_d of a working element is applied perpendicularly to the arm 6. The force P_2 of the rated value spring is applied at an angle α of 60 - 80° and preferably 65 - 75°. The rated value spring is a tension spring which can be elongated in the direction of its force line. Mounted on the lever arm 6 is an electric contact 8 which cooperates with a fixed contact 9. In this arrangement this latter contact also acts as a mechanical stop. The at-rest position is determined by a stop 10 solid with the casing. Consequently, when the snap-over action occurs, the lever 1 can swing through an angle β_0 .

On the left of FIG. 2, the vapour pressure P_d of the working element is plotted against temperature; on the right are illustrated the forces occurring in the snap-action system at different positions and for different settings of the rated value spring. The force curve is shown against the angle of swing β . The range of swing is limited to the angle β_0 . The omega spring 2 has a negative characteristic curve c_{10} in this range. For a first setting of the rated value spring giving a small force P_2 , a force having the characteristic curve c_{21} and acting on the lever 1 is obtained in the range of swing, and for a greater force P_2 the characteristic curve c_{22} is obtained. If the effective characteristic curve for the rated-value spring and the characteristic curve for the omega spring are added together, then for the first setting (small force P_2) the characteristic curve c_{s1} is obtained and for the second setting (large force P_2), the characteristic curve c_{s2} results. The forces determined by these characteristic curves counteract the force of the vapor pressure curve P_d . If, for the first setting, the vapour pressure moves up past to the point a , the system snaps over and the working point moves from b to c . Only when the vapour pressure has dropped below the

point *d* does the system snap back into the initial position. Similar conditions are obtained with the second setting. When the point *e* is exceeded, the system snaps from *f* to *g*. It only snaps back again when the vapour pressure falls below point *h*.

It can be seen from the graph that the steepness of the spring characteristic curves c_{21} and c_{22} acting on the lever diminish as the spring force increases. Consequently, when the spring force is small, a small force difference D_1 results, and with a large force, a large force difference D_2 is obtained. Consequently, the temperature differences Δ_{t1} and Δ_{t2} at which change-over occurs are approximately constant despite the bend in the vapour pressure curve.

The effective spring characteristic curve (steepness decreasing as force increases), here of interest, is obtained by causing the rated value spring to apply force to the lever 1 along a line that is at an angle of α to the lever. Although in this arrangement the force of the rated value spring which counteracts the force P_d varies in proportion to its elongation, the rise in the characteristic curve that takes place in the angle of swing β_0 surprisingly does not remain constant, but decreases as the force increases.

FIGS. 3 and 4 illustrate a practical form of construction of the temperature responsive switch of the invention. In these figures the same reference numerals as in FIG. 1 are used as far as possible for corresponding parts. The lever 1 having two arms 6 and 7 is fitted in a casing 11. The lever 1 simply rests on the bearing 3 solid with the casing, and is drawn towards the fixed bearing 3 with the aid of the rated value springs which take the form of tension springs 26. The rated value springs 26 are held at their other ends by backing elements 12. For the purpose of carrying out the initial adjustment, these backing elements are mounted on screw threaded members 13. The latter members are secured to a slide 14 which can be displaced by means of a cammed disc 15 on an adjusting spindle 16 for the purpose of setting to the required value.

A working element 17 is formed by a tubular bellows 18 and a part 19 of the casing. A capillary tube 20 communicates with a sensor, not illustrated. The temperature of the sensor determines the vapour pressure in the working element 17. The end face of the tubular bellows 18 acts on a raised portion 21 on the lever arm 6. In this arrangement the first step is not formed by a fixed contact 9 but by a part 22 of the casing, which part surrounds a contact system 23. As shown in FIG. 4, the lever arm 6 acts on a plunger 24 which in turn

acts on a spring 25 carrying the movable contact of the system 23.

FIG. 4 parallel shows that two rated-value springs are arranged side-by-side and parallel with each other, and that the stops 10 are disposed symmetrically, one on each side of a line of symmetry.

Instead of the omega spring, another type of snap action spring may be used that has a negative characteristic curve in the working range. The idea underlying the invention may also be applied to snap action systems having a single armed lever, and to such levers in which the lines along which the forces of the working element and the rated value spring run to the same point on the lever.

I claim:

1. A temperature responsive switch assembly comprising a casing, a rigid lever in said casing, pivot means for mounting said lever for pivotal movement relative to a fixed part of said casing, a snap action spring between said lever and said casing, a working element positioned between and connected to said casing and said lever, said working element having a moving part for applying forces to said lever on one side of said pivot means, said working element having a nonlinear vapor pressure curve, spring means attached to said casing and said lever for applying forces to said lever which oppose said working element applied forces to said lever, said spring means forces being applied to said lever on the side of said pivot means opposite said one side, said spring means having a line force forming an angle with said lever so that the reaction response of said spring means parallels said working element nonlinear vapor pressure curve.

2. A temperature responsive switch assembly according to claim 1 in which said lever has two arms forming an obtuse angle with the apex thereof coincident with said pivot means, said working element being in contact with one of said lever arms, said spring means being attached to the other of said lever arms with said line of force thereof being at an acute angle relative to said one of said arms.

3. A temperature responsive switch assembly according to claim 2 wherein said acute angle is within the range of 65° to 75° .

4. A temperature responsive switch assembly according to claim 2 wherein said spring means engages the one of said arms which is remote from said snap action spring, said spring means being generally parallel to the other of said arms.
